TANK CONSTRUCTION

Henry Schmidt, Wilmette, Ill., assignor to International Harvester Company, a corporation of New Jersey

Application June 3, 1938, Serial No. 211,640

13 Claims. (Cl. 137—21)

This invention relates to a device for draining the dry tank of a refrigerating unit. More specifically it relates to a special form of drain body for draining both a dry tank and a refrigerating tank within which the dry tank is positioned.

In refrigerator constructions where there is a dry tank positioned within another tank containing a cooling fluid, it is often necessary to drain both the outer tank of cooling fluid as well as to drain the inner tank of any condensation or water or other fluid used for cleaning. It is possible to provide separate drain systems for each tank, but in this case the apparatus involved may become complicated and unwieldy. It is desirable to make any fittings for draining as compact and simple in construction as possible and yet capable of easy installation.

An object of the invention is to provide an improved drain body for the dry tank and cooling tank of a refrigerator.

A further object is the provision of a compact and simplified drain construction for a pair of tanks, one within the other.

Another object is to provide an improved refrigerator construction involving a compact and simplified drain body.

Other objects will appear from the disclosure.

According to the present invention, a dry tank is positioned within another tank containing a cooling fluid. There are drain openings in each tank. A drain fitting connects each opening and has a separate opening for a drain pipe within the outer tank. There are pipe connections engaging the opening in the outer tank, an outer pipe communicating with the drain pipe for the outer, and an inner pipe communicating with the opening in the drain body from the inner dry tank. These pipes extend out beyond the insulation for the outer tank and have control valves at their ends.

In the drawing:

Figure 1 is a section taken along the line 1—1 of Figure 2, showing the connection of a novel drain body to the drain openings in an inner dry tank and an outer refrigerating tank;

Figure 2 is a section taken along the lines 2—2 of Figure 1;

Figure 3 is a side elevation of the novel drain body;

Figure 4 is a top view of the drain body; and, Fig. 5 is a bottom view of the drain body.

An outer tank 10 has an exterior covering 11 of any suitable insulating material, such as cork, encased within a shell 12. There is an inner

dry tank 13 within the outer tank 10 and a cooling fluid space 14 between the tanks. The inner dry tank 13 has a drain opening 16, to which is suitably joined, as by soldering or welding, a flange member 17. A securing nut 18 is positioned within the flange member 17, having a through opening 19, the upper portion of which is square in section, as at 20, for the reception of an inserting tool. A threaded portion 22 extends through and beyond the flange member 17 into engagement with a novel drain body 25.

This drain body, which may be formed of cast metal, is shown separately in Figures 3, 4 and 5. It includes a short circular section 26, exteriorly threaded. There is a circular threaded opening 27 in this section eccentrically positioned with respect to the outer surface. There is also a passage 28 extending through the short circular section 26 at a part where the distance between the opening 27 and the surface of the circular section is the greatest. Extending upwardly from the passage 28 is a pipe or tubular section having a first portion 30, generally parallel to the axis of the circular portion 26, a second portion 31 extending at right angles to the axis of the circular section and away from it substantially beyond the outer surface of the circular section, and a portion 32 extending parallel to the axis of the circular section and threaded, as at 33, for reception of the threaded section 22 of the nut 19. From the opposite side of the short circular section 26, a tubular or pipe section extends which is composed of a short portion 35 extending generally parallel to the axis of the tubular section 26 and another portion 36 extending toward the axis of the short tubular section. This portion 36 extends at a substantial angle to the portion 31, as seen in Figures 4 and 5. This second pipe section lies entirely within the largest diameter 35 of the short tubular section 26, for a purpose later to be described.

The tubular section 26 extends through an opening 38 in the outer tank 10 and is threaded within a fitting 39 suitably secured, as by soldering or welding, to the exterior surface of the tank 10 and positioned within the layer of insulation around the tank 10. A drain pipe 41 is threaded into engagement with the opening 27 in the short circular section 26. A pipe 42 is connected to the end of the fitting 39 and extends out beyond the shell 12, being welded or soldered thereto by means of a ring member 43. A fitting 44 engages the end of the pipe 42 and has a valve 45 attached thereto.

Extending within the pipe 42 into a threaded engagement with the portion 36 of the fitting 25 is a pipe 47. The outer end of the pipe 47 is supported by means of a nut 48 in the fitting 5 44 and has a valve 49 attached to it.

The operation of the novel drain body in relation to the refrigerant containing tank 10 and the dry tank 13 may be seen from Figure 1. Articles to be cooled are placed in the dry tank 10 13 and cooling is effected by the fluid between the tanks. When the fluid exceeds a certain amount, the excess fluid will pass out through the drain 41, fitting 39, pipe 42, fitting 44, and valve 45. Any condensation in the dry tank 13 15 or fluid used in cleaning the tank will pass off through the drain body 25, pipe 47, and valve 49. If it is desired to drain the tank 10 completely of refrigerant, the overflow pipe 41 is removed.

With the above described arrangement of separate drains, draining of the two tanks may be effected separately and at different times, and yet the draining structure is compact and simple.

This draining structure is also of advantage 25 because it can be easily assembled and disassembled. For disassembling, the drain pipe 41 is unscrewed and removed. This is easily accomplished, because, as seen in Figure 2, the inner dry tank 13 does not extend over the 30 threaded opening 27 of the drain body 25, which receives the end of the over-flow pipe 41. Then, the nut 19 is unscrewed from its connection with the portion 32 of the drain body, any suitable removing tool having a square head to 35 fit the square opening 20 in the nut being employed. Then, the pipe 47, nut 48, and valve 49 are removed. Then, the drain body 25 is unscrewed from the fitting 39. This can be done without the drain body striking the walls 40 of the tank 10, as will be evident from the circle 51, which describes the path of the outermost point of the fitting as it is unscrewed. As previously described, the portions 35 and 36 of the drain body 25, extending below the short tubular section 26, are entirely within the outer 45 diameters of the tubular section 26, and thus may be pulled through the opening in the fitting 39 and the drain opening 38 in the tank 10. Assembly of the tanks and the drain body 50 is accomplished by reversing the order of steps.

It will be apparent from the foregoing description that an improved refrigerator tank construction has been provided, which includes a novel drain body. It is also apparent that the 55 drain body is not limited in use to refrigerator tank constructions, but may be used wherever separate drains are to be provided.

The intention is to limit the invention only within the scope of the appended claims.

What is claimed is:

1. A fitting formed of cast metal comprising a circular section exteriorly threaded and having a first circular opening extending therethrough also threaded and eccentrically positioned with respect to the exterior surface and a second opening extending through the circular section at a portion where there is the greatest width between the circular opening and the exterior surface, a first pipe section extending 65 from the second opening on one side of the circular opening first parallel to the axis of the circular section then at right angles thereto and away therefrom and finally parallel thereto with an internal thread at the end, and a second pipe section extending from the second 70 75 second pipe section

opening on the opposite side of the short circular section first parallel to the axis of the circular section and then toward the axis and being internally threaded at the end, the said second pipe section being entirely within the 5 extension of the outer surface of the short circular section.

2. A fitting comprising a circular section exteriorly threaded and having a first threaded opening extending therethrough and a second 10 opening also extending therethrough, a first pipe section extending from the second opening on one side of the circular section first parallel to the axis thereof, then at right angles thereto and away therefrom, and finally parallel thereto with an internal thread in the end of the pipe section, and a second pipe section extending from the second opening on the opposite side of the circular section first generally parallel to the axis thereof and then at right angles 20 thereto and toward it considerably out of parallel with the portion of the first pipe section at right angles to the axis of the circular section, said second pipe section being entirely within the extension of the exterior surface of the cir- 25 cular section.

3. A fitting comprising a short exteriorly threaded section having a threaded opening and another opening extending therethrough, a first pipe section extending from the said other 30 opening on one side of the short threaded section substantially beyond the largest diameter thereof and terminating in a portion substantially parallel to the axis of the short threaded section, and a second pipe section extending 35 from the said other opening on the opposite side of the short section and terminating in a portion extending generally at right angles to the axis of the short threaded section and generally toward the axis thereof.

4. In combination, a first tank having an opening therein, a second tank positioned within the first tank in spaced relation thereto and having an opening considerably out of alignment with the opening in the first tank, and a 45 fitting having a first section engaging the opening in the outer tank and provided with a pair of openings and having a first pipe section extending from one opening at one side of the first section beyond the largest outer diameter 50 of the first section into engagement with the opening in the inner tank, and having a second pipe section extending from the same opening at the opposite side of the first section and being entirely within the largest diameter of the 55 first section and terminating in a portion extending generally at right angles to the openings in the first section.

5. In combination, a first tank having an opening in one wall thereof spaced a certain 60 distance from one adjacent wall, a second tank positioned within the first tank in spaced relation thereto and having an opening in a surface generally parallel to the surface having the opening in the first tank, the opening in the 65 wall of the second tank being offset from the opening in the wall of the first tank an amount no greater than the distance between the opening in the wall of the first tank and the closest wall thereof, a fitting having a first section engaging the opening in the outer tank, provided with a pair of openings, and having a first pipe section extending from one opening at one side of the first section outwardly beyond the opening in the one wall of the outer tank an amount 70 75

no greater than the distance between said opening and the nearest wall of the tank into engagement with the opening in the inner tank, and a pipe positioned between the tanks and engaging the other opening of the first section 5 of the fitting.

6. In combination, a pair of tanks positioned one within the other and each having an opening in one wall, and a pipe fitting engaging and connecting the two openings and having an opening in the portion engaging the outer tank separate from the portion of the pipe fitting connecting the two openings in the tanks, and a pipe positioned between the tanks and engaging the said 10 opening in the pipe fitting.

7. In combination, a pair of tanks positioned one within the other in spaced relation and each having an opening in one wall, a first fitting engaging the openings in the tanks with a 15 through passage extending between the tanks and a separate opening in the portion engaging the opening in the outer tank, a pipe extending in the space between the tanks engaging the opening in the fitting, a second fitting engaging the opening in the outer tank at the exterior thereof and being in communication with the opening through the first fitting, and a third fitting positioned within the second fitting in 20 engagement with the first fitting and communicating with the passage from the inner tank.

8. In combination, a pair of tanks positioned one within the other, and each having a drain opening, there being a space between the tanks, draining means for the outer tank engaging the 25 drain opening therein and extending exteriorly thereof, draining means for the inner tank engaging the drain opening in the inner tank and extending through the draining means for the outer tank, and conduit means engaging the drain opening in the outer tank and extending in 30 the space between the tanks.

9. In combination, an outer tank having a drain opening and a substantial layer of insulation on the outside of the tank, an inner tank 35 positioned within and in spaced relation to the outer tank at least partially uncovering the drain opening in the outer tank and also having a

drain opening, a drain fitting having a first section engaging the opening in the outer tank, a first pipe section extending from a first opening in the first section into engagement with the opening in the inner tank and a second pipe 5 section extending from the same opening in the first section on the opposite side thereof, and a second opening in the first section uncovered by the inner tank, a drain pipe extending in the space between the tanks and engaging the second opening in the drain fitting, pipe means engaging the opening in the outer tank in communication with the drain pipe and extending through the insulation layer on the outer tank, and a pipe within the pipe means engaging the 10 second pipe section of the drain fitting.

10. In combination, a first tank having an opening in the bottom thereof, a second tank containing the first tank and having an opening in the bottom thereof, and a fitting having 20 a first section engaging the opening in the bottom of the second tank and provided with a pair of openings, one of which is offset laterally from the first tank, said fitting also having a pipe section extending from the other opening into 25 engagement with the opening in the bottom of the first tank.

11. The combination as set forth in claim 10, including a pipe engaging the opening in the fitting offset laterally from the inner tank and 30 extending upwardly from the bottom of the second tank between the sides of the tank.

12. In combination, inner and outer tanks, each having an opening in the bottom thereof, there being a space between the sides of the 35 tanks, a fitting extending between the openings and providing a passage from the bottom of the inner tank through the bottom of the outer tank and having an opening separate from the passage providing a drain for the outer tank and having 40 its axis extending through and along the space between the sides of the tanks.

13. The combination as specified in claim 12, including a pipe engaging the said opening in the fitting and extending upwardly in the space 45 between the sides of the tanks.

HENRY SCHMIDT,
